TEAPOT OR THE LIKE

Mary Jane Winans, La Canada, Calif., assignor to Glad-ding, McBean & Co., Los Angeles, Calif., a corporation of California

Application October 13, 1958, Serial No. 52,937

Term of patent 14 years

(Cl. D44—26)

Fig. 1 is a side view of a teapot showing my new design;

Fig. 2 is a perspective view taken from the front thereof;

Fig. 3 is a perspective view taken from the rear thereof.

Fig. 4 is a sectional view taken in the plane indicated by line IV—IV of Fig. 1.

Fig. 5 is a sectional view taken in the plane indicated by line V—V of Fig. 1.

Fig. 6 is a sectional view taken in the plane indicated by line VI—VI of Fig. 1.

I claim:

The ornamental design for a teapot or the like, as shown.
